206,812

COMBINED TOY WHEELED VEHICLE AND SLED

Donald R. Keller, 1441 Forbes Road,
Lexington, Ky. 40505

Filed Dec. 20, 1965, Ser. No. 245

Term of patent 14 years

(Cl. D34—15)

FIG. 1

I claim:

The ornamental design for a combined toy wheeled vehicle and sled, substantially as shown and described.
